JOSEF KÖHLEN, OF HERNE IN WESTPHALIA, GERMANY

PNEUMATICALLY ACTUATED PERCUSSIVE TOOL

Application filed June 17, 1930, Serial No. 461,752, and in Germany June 17, 1929.

My present invention relates to pneumatically actuated percussive tools of the kind in which separate floating valves, opened by the reduction of pressure in the cylinder when exhaust occurs on one or other side of the plunger, control respectively the working stroke and the return stroke of the plunger, and the distinctive feature of the invention, in its broadest aspect, consists in the provision of comparatively small relief ducts which lead into the cylinder from the valve chambers, the valves being between these ducts and the main ducts or ports through which air flows to the cylinder when the valves are open. According to the position in which the said relief ducts open into the cylinder a considerable variety of effects can be obtained with regard to the timing of the plunger action, that is to say with regard to the positions in which the plunger movement is reversed, and this feature can be utilized to design the apparatus for obtaining the best efficiency for different kinds of work. In so designing apparatus, the positions of the openings of the said ducts into the cylinder may be determined independently of each other.

It is not broadly novel to provide relief ducts in connection with pneumatic hammers, such ducts having heretofore been used, opening from the valve chambers into the atmosphere. It has also been proposed, in connection with a pneumatic hammer having two piston-valves, to have ducts leading from the valve chambers to the cylinder, so that compression in the cylinder acts on the valves. The present invention differs from this in that it is concerned only with tools having floating valves opened by reduction of pressure in the cylinder.

The invention constitutes an important advantage in connection with pneumatically actuated percussive tools having floating valves. It enables the air passage at the valve seats to be made substantially larger, so that air can be admitted at a higher rate without throttling. In the case of hammers with a single valve the size of the air passage must not exceed a certain limit, as otherwise, when exhaust takes place from one or

other cylinder chamber, the energy of the air streaming through the passage at the valve seat will prevent the valve from returning to its seat, only a comparatively small annular area of the valve being available for the thrust which is to return it. With the invention this area can be increased to

$$\pi \frac{d^2}{4}$$

so that the power available for returning the valve is represented by

$$p\pi \frac{d^2}{4}$$

where p is the pressure in the air-supply pipe and d is the diameter of the valve, say a ball valve.

Another advantage consists in the fact that the valve positions may be changed before the exhaust ports of the cylinder are opened, or that at least the valve movements may be initiated in advance of the exhaust, the valves beginning to move by reason of the normal fall of pressure in the cylinder due to friction plus conversion of static pressure into kinetic energy. Consequently cut-off occurs or is started before exhaust, or coincides with exhaust, saving the loss of air which otherwise occurs through live air streaming past the valve after opening the exhaust port. In certain circumstances the invention even enables expansion to be utilized for driving the plunger.

Various methods are available for carrying the invention into effect. The relief ducts may be in permanent communication with the air-supply pipe, but this involves some loss of live air during exhaust, which may be prevented by making the valves close the ducts except when supply is taking place to the respective cylinder chambers, the flow of air through the ducts then increasing the supply.

Another advantage of the invention is that the movement of the valve controlling supply to the front cylinder chamber can be made shorter, so that there is a reduced supply to this chamber, the same being needed only for the return stroke of the plunger.

Where there is a single valve this effect can only be obtained by making the passage through one valve seat smaller than the other, which has disadvantages.

5 It is with the invention possible to make the valve movements take place asynchronously.

10 The invention is illustrated in the annexed drawings, which show two forms of construction in section, in Fig. 1 and in Fig. 2 respectively.

15 Referring first to Fig. 1, the cylinder 1 contains the plunger 2, which is driven by compressed air and strikes a tool not shown

20 in the drawings. Compressed air is admitted to the annular distribution spaces 3 surrounding the two valve chambers 4 and 5, preferably by a channel (not shown) arranged on the cylinder mantle and connecting

25 said distribution spaces. This channel is provided with an air admission pipe (likewise not shown) arranged opposite the exhaust ports disposed in the cylinder wall. In the valve chamber 4 is arranged a ball

30 valve 6 for controlling the working stroke and in the valve chamber 5 a ball valve 7 for controlling the return stroke. Each valve is in its valve chamber exposed on all sides to the compressed air admitted thereto from the

35 distribution space 3 surrounding it. Each of the valve chambers 4 and 5 is provided with a small duct *a* and *b* communicating with the annular distribution space 3 on the side of the ball valves 6 and 7 opposite to the ports 13 and 17.

40 The plunger moves in the direction indicated by the arrow for delivering the blow, and is shown at the end of its working stroke. In this position the rear face 8 of the plunger

45 has moved past an exhaust port 9, and owing to the fall of pressure in the cylinder the ball valve 6 is thrust against its seat 10, cutting off the flow of compressed air to the cylinder.

50 A small duct 11 in the cylinder wall also allows discharge of air from above the valve arranged in the valve chamber 5, and this valve is consequently lifted from its seat 12, allowing compressed air to flow through a port 13 and drive the plunger 2 back. In due

55 course the front face 14 of the plunger uncovers an exhaust port 15, and the valve 7 drops back on to its seat 12, cutting off the inflow of compressed air through the port 13, the duct 11 being at this time closed by the

60 plunger. The plunger, moving by virtue of its momentum, uncovers a small duct 16, which allows air to escape from under the valve 6, so that this valve drops from its seat 10, and compressed air flows through the port 17 for imparting the next working stroke.

65 The valve 7, admitting air for the return stroke of the plunger, is of smaller diameter than the valve 6, which admits air for the working stroke, the power required

for the return stroke being commonly less than that required for the working stroke.

Whereas in the construction shown in Fig. 1 the small ducts 11 and 16 are continuously in communication with the compressed air supply pipe, the corresponding ducts 11' and 16' in the modification shown in Fig. 2 are controlled by the ball valves 6 and 7, so that they are only open to the supply pipe while compressed air is being supplied to those parts of the cylinder into which they lead.

This saves loss of compressed air, and increases the effective supply to the cylinder. The mode of operation is substantially the same as described with reference to Fig. 1.

80 The plunger is shown in a position in the course of the working stroke, with the valve 7 resting on its seat 12, and the valve 6 dropped from its seat 10 on to a seat 10'.

85 When the plunger uncovers the exhaust port 9 both the valves 6 and 7 are lifted, and the valve 7, held against a seat 12', prevents further flow of air through the duct 11' to the top of the cylinder, whereas air flows through

90 the port 13 to the bottom of the cylinder, which also receives a small amount of air through the duct 16', previously cut off from the air supply by the ball 6 resting on the seat 10'.

95 The valve seats 12', 12, 10 and 10' may be so proportioned that the valves 6 and 7 open and close at different times. The valve 7 is shown as having only a very small movement, the amount of air required for the return stroke being small.

100 Broken lines in Fig. 2 indicate a further modification wherein the small duct of the valve chamber 5, designated 11'', opens into the cylinder below the upper exhaust port 9.

105 This modification is particularly suited for pneumatic hammers with a long stroke. The effect thereof is that the valve 7 is not opened till the plunger has reached the end of the power stroke. When the plunger

110 clears the port 9 there is at first only a small admission of compressed air in front of it, through the duct 16', the port 13 remaining closed, so that admission from this port does not impede the final stage of the plunger movement.

115 The positions in which the small ducts open into the cylinder are of course always arranged in accordance with the particular work for which the apparatus is designed.

120 It will be clear that valves other than ball valves may be used, and that the valves may be placed in any convenient position, e. g., both on the same side of the cylinder. The drawings are in this respect purely diagrammatic.

125 In some cases it may be desirable to duplicate the valves, that is to say to have two groups of valves instead of two single valves, the valves in each group being in parallel.

130

I claim:—

1. A pneumatically actuated percussive tool, comprising a cylinder, a plunger reciprocating in said cylinder, a valve chamber communicating with the rear cylinder chamber by a main air inlet port and with the front cylinder chamber by a relief duct, a second valve chamber communicating with the front cylinder chamber by a main air inlet port and with the rear cylinder chamber by a relief duct, a floating valve arranged in the first named valve chamber for controlling the working stroke, and a floating valve arranged in the second valve chamber for controlling the return stroke and adapted to operate independently from the valve controlling the working stroke, of which valves each is adapted to change its seats when the main air inlet port of the one valve chamber and the relief duct of the other valve chamber are put in communication with the same exhaust port by the withdrawal of the plunger from the cylinder chamber into which they open and each valve is adapted to close the relief duct of its valve chamber except when the cylinder chamber to which said relief duct leads is receiving compressed air from the main air inlet port of the other valve chamber.
2. A pneumatically actuated percussive tool, comprising a cylinder, a plunger reciprocating in said cylinder, a valve chamber communicating with the rear cylinder chamber by a main air inlet port and with the front cylinder chamber by a relief duct, a second valve chamber communicating with the front cylinder chamber by a main air inlet port and with the rear cylinder chamber by a relief duct, a ball valve arranged in the first named valve chamber for controlling the working stroke, and a ball valve arranged in the second valve chamber and executing a smaller lineal movement than the ball-valve controlling the working stroke and adapted to operate independently from the last named ball valve, of which valves each is adapted to close the relief duct of its valve chamber except when the cylinder chamber to which said relief duct leads is receiving compressed air from the main air inlet port of the other valve chamber.
3. A pneumatically actuated percussive tool, comprising a cylinder, a plunger reciprocating in said cylinder, a valve chamber communicating with the rear cylinder chamber by a main air inlet port and with the front cylinder chamber by a relief duct, a second valve chamber communicating with the front cylinder chamber by a main air inlet port and with the rear cylinder chamber by a relief duct, a floating valve arranged in the first named valve chamber for controlling the working stroke, and a floating valve arranged in the second valve chamber for controlling the return stroke, each of said

valves being adapted to change its seats when the main air inlet port of the one valve chamber and the relief duct of the other valve chamber are placed in communication with the same exhaust port by the withdrawal of the plunger from the cylinder chamber into which they open, and each valve chamber having a duct therein communicating with the air inlet and constantly on a side opposite to the inlet ports.

In testimony whereof I affix my signature.

JOSEF KÖHLEN.
